UNITED STATES PATENT OFFICE

WALTER B. KNOX, OF PITTSBURGH, PENNSYLVANIA

BRUSH

Application filed November 26, 1927. Serial No. 235,852.

The present invention relates broadly to the art of brushing and scrubbing, and more particularly to fountain brushes or mops especially adapted for the washing or cleaning of finished surfaces.

It has heretofore been proposed in the art to construct brushes of the general character herein contemplated by providing a single elongated body of material slipped on to a suitable handle portion, and also to provide a cleaning head in the form of a plurality of overlapping convolutions. I find that while both of these constructions possess certain advantages, there are objections inherent to the use thereof. With the elongated body of material there is no predetermined shape and considerable difficulty is encountered, particularly when the parts are wet, in slipping the body into position onto the handle. The plurality of convolutions, while it is self-sustaining, thereby enabling it to be placed into position on a handle, or removed therefrom irrespective of whether it is wet or dry, is extremely difficult to assemble properly. Also, the inner convolutions impart an undue amount of rigidity to the outer convolution thereby making the operation of threading the body into position on a hook-shaped handle, rather difficult.

The present invention is directed to a brush involving the inherent desirable characteristics of brushes as hereinbefore constructed, and at the same time obviating the objections referred to, by utilizing a cleaning body comprising a single coil of material with its ends held in adjacent relationship, and having supporting means of such character that the necessary flexibility is insured to permit easy application and removal of the head while preventing any objectionable distortion of the head when it is removed from the handle.

In the accompanying drawings, I have shown for purposes of illustration only, certain preferred embodiments of the present invention, it being understood that the drawings do not define the limits of my invention, as changes in the construction disclosed there-

from the spirit of my invention or the scope of my broader claims.

In the drawings:

Figure 1 is a top plan view of the head removed from the handle.

Figure 2 is a perspective view of the handle itself.

Figure 3 is a side elevational view of the head and handle in partly assembled relationship.

Figure 4 is a transverse sectional view of a line IV—IV of Figure 1.

Figure 5 is a top plan view of a modified embodiment of my invention; and

Figure 6 is a detail sectional view along the line VI—VI of Figure 5.

In accordance with the present invention, the mop-head, as shown in Figure 1, may comprise an edge piece or strip 2 having a passage 3 extending longitudinally therethrough, the edge serving as a binder for the desired cleaning threads or strings 4.

The head preferably comprises an elongated body or strip of material having its ends 5 secured in adjacent relationship to provide a substantially single coil. Preferably, the adjacent ends are secured together in overlapping relationship, as shown in Figure 1, whereby the coil is in the shape of a single convolution with the adjacent ends offset both laterally and peripherally one with respect to the other. Due to the comparatively small area of overlap in a construction of this character, no difficulty is encountered in effectively securing the adjacent ends together in such manner as to prevent relative displacement between the same.

The single coil is extremely desirable due to its flexibility which permits the same to be threaded easily onto the hook-shaped end 6, carried by handle 7. Where the coil is in the shape of a convolution, it will be apparent that a relative turning movement between the head and hook is effective either for applying or removing the body. Due to the absence of inner convolutions, the ends may move slightly relative to each other during the application or removal of the head, thereby facilitating such an operation. This is particularly true if the connection between

the ends is such as to permit the end which first receives the hook to move upwardly slightly and the opposite end to move downwardly slightly whereby the hook may ride over the lower end. This condition is clearly shown in perspective in Figure 3.

While a single coil of the character described possesses inherent advantages, I have found that extremely desirable results may be obtained by the utilization of means supplemental to the head for maintaining such coil in predetermined shape. Such means, where provided, is preferably flexible to permit the described slight movement of the different parts of the coil as desired to facilitate application or removal of the head. In Figure 1 said supporting means is shown in the form of a filler 8 which may conveniently comprise a length of resilient wire 9 or the like upon which a second strip of material 10 is placed. The opposite ends of the filler may be secured to the coil as indicated in Figure 4, preferably at points spaced from the ends thereof. In this manner collapse of the coil is prevented, while the yielding relationship of the ends is maintained.

In Figures 5 and 6 there is illustrated a slightly modified embodiment of the invention in which the flexible support for the coil is obtained by the use of a flexible insert 11 conveniently in the form of a spiral spring inserted in the opening 4' in the strip 2'. Such spring when used preferably has an internal diameter substantially equal to but slightly greater than the external diameter of the hook 6, and is of such nature as to provide an adequate support for the coil without interfering with the desired relative movement.

It will be apparent to those skilled in the art that the spring supporting means may be utilized either by itself, in the form illustrated in Figure 5, or in combination with the filler as shown in Figure 1.

From the foregoing specification it will be apparent to those skilled in the art that I provide a body preferably in the form of a single coil of convolute shape with the adjacent ends of the strip or body comprising the coil secured permanently together in such manner as to permit a slight relative yielding movement therebetween either laterally, vertically or circumferentially.

I also preferably provide such a single coil with supporting means, conveniently of a flexible or yielding nature. Where said supporting means is in the form of a filler, it is conveniently secured substantially transversely of the coil so that its ends contact with the coil at points circumferentially spaced from the ends of the coil to thereby permit relative movement of the ends as set forth.

I claim:

1. In a brush, a head comprising an elongated body of fibrous material having its ends secured one to the other to form a continuous

coil comprising a single thickness only of body material throughout its entire length, said ends being flexibly secured together to permit a slight relative yielding movement thereof, one end being offset radially from the center of the coil a greater distance than the other. 70

2. In a brush, a head comprising an elongated body of fibrous material having its ends secured one to the other to form a continuous coil comprising a single thickness only of body material throughout its entire length, said ends being flexibly secured together in overlapping relationship to permit a slight relative yielding movement thereof, and means supplemental to said body for maintaining the same against collapse. 75

3. In a brush, a head comprising an elongated body of material having its ends secured together to form a coil comprising a single thickness only of body material throughout its entire length, said ends being secured to each other to permit a slight relative yielding movement thereof, said coil having a hollow seam to adapt it for the reception of a hook and means supplemental to said body for maintaining the same against collapse, said means comprising a flexible insert within said coil and extending substantially transversely thereof, and secured thereto at points spaced from the ends of said coil. 85

4. In a brush, a head comprising a single coil only of body material having its adjacent ends secured to each other in overlapping relationship to permit slight relative movement of said ends, and supporting means for said coil, said coil having a hollow seam for the reception of a hook, the overlapping of said ends positioning one end of the hollow seam so as to be freely accessible outside of the line of the other coil end. 100

5. In a brush, a head comprising an elongated body of material having its ends secured together to form a coil comprising a single thickness only of body material throughout its entire length, said ends being secured to each other to permit a slight relative yielding movement thereof, means supplemental to said body for maintaining the same against collapse, said means comprising a flexible insert within said coil and extending substantially transversely thereof, said coil having a hollow seam to adapt it for the reception of a hook, and a handle having a hook-shaped portion adapted to slide into said hollow seam by a relative turning movement of the head and handle. 110

6. In a brush, a head comprising an elongated body of material having its ends secured together to form a coil comprising a single thickness only of body material throughout its entire length, said ends being secured to each other to permit a slight relative yielding movement thereof, means supplemental to said body for maintaining the 125

same against collapse, said means comprising a flexible insert within said coil and extending substantially transversely thereof, and secured thereto at points spaced from the ends of said coil, said coil having a hollow seam to adapt it for the reception of a hook, and a handle having a hook-shaped portion adapted to slide into said hollow seam by a relative turning movement of the head and handle.

5 7. As an article of manufacture, a brush comprising a head composed of an elongated body of material having its ends secured in adjacent substantially radially offset relationship to provide a substantially continuous coil of a single thickness only of body material throughout substantially its entire length, said offset ends having openings for the reception of a hook shaped handle portion.

10 20 In testimony whereof I have hereunto set my hand.

WALTER B. KNOX.
